ALFRED BÜCHI, OF WINTERTHUR, SWITZERLAND, ASSIGNOR TO BUSCH-SULZER BROS.
DIESEL ENGINE COMPANY, OF ST. LOUIS, MISSOURI, A CORPORATION OF MISSOURI.

COMBUSTION-ENGINE.

1,142,873.

Specification of Letters Patent. Patented June 15, 1915.

Application filed June 1, 1912. Serial No. 700,822.

To all whom it may concern:

Be it known that I, ALFRED BÜCHI, engineer, a citizen of the Republic of Switzerland, residing at Winterthur, Canton of Zurich, Switzerland, have invented certain new and useful Improvements in Combustion-Engines, of which the following is a full and concise specification, as required by statute.

10 This invention is an improvement in combustion engines, such as Diesel engines, and relates more particularly to the means for supplying and controlling the air employed for injecting the fuel therein, the object being to provide one or more receivers or storage reservoirs in or connected to the fuel air injection line, together with suitable control mechanism therefor as later explained, whereby such storage receptacle may be cut 15 into or out from connection with such line according to the needs of the engine under variations of the load or other conditions. Storage capacity in the fuel injection air line is desirable for obvious reasons and 20 also usual, but on sudden change of load it retards the quick adjustment of the fuel introduction that is necessary for efficient control. In order to accommodate a rapid change in the load a corresponding rapid 25 change must be made in the pressure of the fuel injection air.

An exemplification of the present invention is shown by the accompanying diagrammatic drawings, wherein—

30 Figure 1 represents a Diesel type engine showing the fuel valve and air supply mechanism equipped with a controlled storage receptacle connected to the injection air line; Figs. 2, 3 and 4 are diagrams of different 35 positions of a control mechanism capable of carrying out the principle of the invention; and Fig. 5 an axial section to illustrate a suitable construction of such mechanism.

The engine cylinder is shown at *a*, its 40 piston at *q*, its fuel valve at *b*, its fuel valve lever at *d*, and fuel cam at *c*, all arranged in the conventional way. The fuel oil is supplied to the valve by a pipe *s* as usual and the injection air, for atomizing and injecting the fuel into and against the cylinder compression is supplied by the multi-stage air compressor *e* through an air line *f*. The compressor may or may not be driven by the crankshaft of the piston *a* according 45 to circumstances.

The storage reservoir or receiver *g* is connected with the air line *f* through a control device *h* which is subject to control either automatically or manually to shut the said reservoir on, partially or entirely, during 50 a change in the load on the engine and the regulation of the injection pressure.

The control device also, in the case illustrated, serves to put the reservoir into communication with the air line when the pressure in the latter falls below the minimum necessary for the engine's operation. The reservoir may itself, be supplied with pressure from the air line, or from a separate reservoir under higher pressure.

As shown for example in Figs. 2, 3, 4 and 5, the said control device comprises a suitable valve casing, indicated diagrammatically by *n*, in which are mounted two concentric valve members *o* and *p*, both of 60 which are adapted to open and close communication, under proper relative conditions, from reservoir *g* to fuel air line *f*. The valve *o* is fitted to the bore of the casing *n*, and the valve *p* is fitted to the interior of 65 the valve *o*, and each is ported as indicated, thus providing a compound valve mechanism to control the reservoir connection. One of the valve members, for instance *o*, is provided with an operating lever *m* linked 70 to a piston *k* in a cylinder which is connected to the air line *f* by a pipe *f'*. A spring *l* tends to urge such piston to the left against the air line pressure. The other valve member *p* is likewise provided with 75 an operating lever *i*, which may be manually controlled, but is shown as linked to the bell crank *t* of a governor *r*.

Upon the starting of the engine, as also at very slow speed and heavy load, the relative positions of the parts would be as indicated by Fig. 2, wherein the governor collar is in a low position and the piston *k* in its extreme, or nearly its extreme, right hand position compressing the spring *l* as the effect of the high pressure in pipe *f*. With increasing speed the governor collar would gradually rise, turning the valve *p* toward the position indicated in Fig. 3 and gradually shutting off the passage from the reservoir to the air line *f*, leaving the air for injection to be supplied directly from the air pump *e* to the fuel valve. The valve *p* under such conditions coöperates with the 80 port openings of the valve *o* as will be evi- 85 90 95 100 105 110

dent, which valve remains in the position indicated until a drop in the pressure in the air line pipe *f* takes place, upon which the spring *l* presses piston *k* to the left, moving 5 lever *m* accordingly and thereby shifting its port openings in the direction to open or enlarge the passage between the reservoir and the air line. It will be evident that through 10 such operation of the two valve-members a position of equilibrium will ultimately be established, wherein they will establish and maintain a balance of pressure in the air line *f* to suit the load and speed of the engine.

15 When the load varies and assuming for instance a sudden decrease to zero, the pressure existing in the air line pipe would be, at the moment of change, sufficient to hold the valve *o* in its extreme right-hand position, while the increasing governor speed 20 would shift valve *p* to its extreme position, both valve-members being then in the relative positions indicated in Fig. 2, and the reservoir cut off. The pressure in the pipe *f* 25 can thereafter fall or may be reduced instantly to such extent as may be desired, but only to that point where the tension of the spring is sufficient to move the piston to the left and thereby restore the pressure from 30 the reservoir as shown by Fig. 3. The tension of the spring, which may be adjustable, is set to correspond with the lowest air line pressure necessary for running the engine, and upon any decrease, such as from the 35 failure of the air compressor or from any other cause, the reservoir *g* will be instantly cut into operation regardless of the speed on the governor at that moment.

It will thus be evident that the invention 40 compounds two functions of control upon the air supply of the fuel injection apparatus and that the same are adapted to operate conjointly and differentially to the end of maintaining desirable pressure conditions in 45 the injection air line, as above stated, and as shown in the drawings.

I claim:

1. In a combustion engine, the combination, 50 with a cylinder having fuel injection means, a fuel supply line, a fuel injection air line and a reservoir connected with the latter line, of a control device for shutting the reservoir off from the air line during change in the load on the engine.

55 2. In a combustion engine, the combination

with a cylinder having a fuel injection valve and a fuel line connected therewith, of an air compressor, a fuel injection air line connecting the same to the fuel valve of the engine and an air reservoir, in combination 60 with a compound valve mechanism controlling the communication between the reservoir and the air line, and means for controlling said valve mechanism according to the pressure in the air line and the speed of the 65 engine.

3. In a combustion engine, the combination with a cylinder having fuel injection means, a fuel injection air line leading thereto, an air compressor for supplying 70 said air line, and a reservoir having a branch connection with the air line, of a control device for shutting off the branch communication of the reservoir from the air line during change in load on the engine. 75

4. In a combustion engine, the combination with a cylinder having fuel injection means, a fuel injection air line leading thereto, an air compressor for supplying said air line, and a reservoir having a branch connection with the air line, of a control device comprising 80 two independently movable valve members jointly controlling the branch communication of the reservoir with the air line, means acted upon by the pressure in 85 said air line for operating one of the valve members, and separate means for operating the other valve member.

5. In a combustion engine, the combination with a cylinder having fuel injection means, a fuel injection air line leading thereto, an air compressor for supplying said air line, and a reservoir having a branch connection with the air line, of a control device comprising two independently movable valve 90 members jointly controlling the branch communication of the reservoir with the air line, a governor and connections for operating one of said valve members, and a fluid pressure device in communication with the air 95 line near the cylinder and connected with the other valve member. 100

In testimony whereof, I have signed this specification in the presence of two witnesses.

ALFRED BÜCHI.
